(57) **CLAIM**

I claim the ornamental design for a shoe upper, substantially as shown and described.

DESCRIPTION

FIG. 1 is a perspective view of a first implementation of a shoe upper according to my design;

FIG. 2 is a front view of the first implementation of the shoe upper;

FIG. 3 is a back view of the first implementation of the shoe upper;

FIG. 4 is a right view of the first implementation of the shoe upper;

FIG. 5 is a left view of the first implementation of the shoe upper;

FIG. 6 is a top view of the first implementation of the shoe upper; and,

FIG. 7 is a bottom view of the first implementation of the shoe upper.

The broken lines shown in the drawings are for purposes of illustrating use and environment only and form no part of the claimed design.
